Patented Aug. 31, 1915.

UNITED STATES PATENT OFFICE.

FRANK SANDT, OF KENOSHA, WISCONSIN.

REVERSIBLE BED-RAIL FASTENING.

1,152,123.

Specification of Letters Patent. Patented Aug. 31, 1915.

Application filed October 30, 1914. Serial No. 869,353.

To all whom it may concern:

Be it known that I, FRANK SANDT, a citizen of the United States, residing at Kenosha, in the county of Kenosha and State of 5 Wisconsin, have invented certain new and useful Improvements in Reversible Bed-Rail Fastenings, of which the following is a specification.

This invention relates to metallic bedsteads wherein the side rails are made of angle-bars and have a detachable wedge and socket connection with the head and foot pieces of the bedstead. Some makes of bed springs require that these side rails be positioned with the angle opening upwardly, while with other bed springs it is necessary that the side rails be placed in an inverted position, that is to say, with the angle opening downwardly. To meet these conditions 10 manufacturers are at present making two styles of side rails adapted to be associated with the head and foot pieces of the bed in reversed positions, as above explained. This necessitates the carrying in stock, both by 15 the manufacturer and the dealer, of a double number of side rails of each finish or color in order that the particular style of side rail desired may be furnished. Obviously this entails double work and double capital invested, which in the case of large manufacturers amounts in the aggregate to a considerable sum of money. To overcome this 20 difficulty it has been proposed to make the connection between the side rails and the end-pieces of the bedstead reversible, so that a single type of side rail may be manufactured and sold, being capable of adjustment to adapt it for any style of bed spring which it is desired to use. None of these reversible 25 constructions heretofore proposed, however, has been found practical, either on account of excessive cost of manufacture, insufficient strength, or difficulty of adjustment in reversing the fastening.

45 It is the object of my invention to provide a simple, cheap, strong and easily reversible bed-rail fastening which is thoroughly practical in every respect.

In the accompanying drawings, Figures 1 50 and 2 are perspective views illustrating, in two different positions, a side rail attached to an end-piece of a bedstead by reversible means embodying the features of my invention. Fig. 3 is a perspective view illustrating the three parts at one end of a bed rail

separated from each other. Fig. 4 is a longitudinal central vertical sectional view through one end of the rail, and Fig. 5 is a similar view illustrating another form of rail.

In Figs. 1 and 2, 6 illustrates one of the metallic corner posts of a bedstead to which is rigidly secured a socket member 7. The side rail comprises the angle-bar body 8 having heads 9 rigidly fixed on opposite ends thereof. These heads may be malleable and fixed in place by rivets 10, or they may be cast directly onto the end of the body 8, as shown in Fig. 5. In the latter case, the thickness of the head longitudinally of the rail is greater. At the end of each head 9 is secured a wedge member adapted to fit into a socket 7. Each of these wedge members consists of a conical body portion having a plane inner face 12 adapted to abut against the end of the head 9 and having at about the mid-portion of the face 12 a rectangular boss or projection 13 from the end of which extends a threaded stem 14. This stem and boss are cast in 65 an integral piece with the body portion of the wedge member 11. The head 9 is provided with a central rectangular opening 15 adapted to receive the boss 13, and a wing-nut 16 is threaded onto the stem 14 to securely bind the wedge to the head 9, said wing-nut bearing against the inner face of the head. It will be seen that the boss 13 fitting in the opening 15 prevents rotation 70 of the wedge with relation to the rail, and inasmuch as said boss is cast integral with the wedge and the weight on the side rail is applied close to the wedge, a very strong and durable construction is provided. The wedge may be quickly and easily reversed 75 by loosening the nut 16 sufficiently to permit withdrawal of the boss 13 from its opening, in the forms shown in Figs. 1 to 4, or by removing the nut in the form shown in Fig. 5, when the boss may be re-inserted in the 80 opening after inverting the wedge and the nut 16 again tightened up to lock the wedge to the head.

Whenever a manufacturer or dealer sells a bed to be used with a known type of bed spring, the wedges will be adjusted on the side rails to the proper position. Only one type of rails need be manufactured and carried in stock, thus reducing the amount of machinery required, the amount of labor, 105 110

and the amount of capital necessarily tied up in extra bed rails under the present system.

I claim as my invention:

- 5 1. In a bedstead, the combination with a corner piece having a socket thereon, of a bed-rail having a head fixed to one end thereof, said head having a non-circular opening extending therethrough lengthwise 10 of the rail, a wedge member comprising a body portion adapted to removably fit in said socket and arranged to abut against said head and be adjustably carried by the head, a non-circular projection rigidly fixed 15 to said body portion and adapted to enter said opening in the head in inverted positions, and an integrally threaded stem extending from the end of said projection, and a nut threaded on said stem and bearing 20 against said head at the opposite side from said body portion of the wedge for rigidly binding the wedge to the head, said projection being withdrawable from its opening when said nut is loosened to permit of turning 25 the wedge with relation to the head into an inverted position.
2. A metallic bed rail having an enlarged head on one end thereof, provided with a

non-circular opening passing therethrough in a direction extending longitudinally of the rail, a wedge member comprising a conical body portion having a plane face adapted to abut against the outer end face of said head, a non-circular projection on said body portion at about the middle of said plane face, a threaded stem on the end of and aligned with said projection, said stem and projection being cast in a single integral piece with said body portion, the stem being arranged to pass through said opening and the projection being arranged to fit in said opening to prevent rotation of the wedge with relation to said head, and a nut threaded 40 on said stem and bearing against the inner face of said head for securely binding the wedge to the head, said projection being withdrawable from its opening when said nut is loosened to permit of reversal of the wedge.

In testimony whereof, I hereunto set my hand in the presence of two witnesses.

FRANK SANDT.
